(57) **CLAIM**

We claim the ornamental design for a refrigerator, as shown and described.

DESCRIPTION

FIG. 1 is a perspective view of a refrigerator showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view thereof in condition of use, where the inside of the door is visible;

FIG. 9 is a perspective view with the outer door thereof opened; and,

FIG. 10 is a perspective view with each of the inner and the outer doors thereof opened.

The broken lines represent unclaimed portions of the refrigerator and form no part of the claimed design.

1 Claim, 9 Drawing Sheets---
